ATTY.

UNITED STATES PATENT OFFICE.

ALEXANDER E. BLOCK, OF ST. LOUIS, MISSOURI.

BUNION-PROTECTOR.

1,237,285.

Specification of Letters Patent. Patented Aug. 21, 1917.

Application filed November 25, 1914. Serial No. 873,912.

To all whom it may concern:

Be it known that I, ALEXANDER E. BLOCK, a citizen of the United States, and a resident of St. Louis, State of Missouri, have invented 5 certain new and useful Improvements in Bunion-Protectors, of which the following is a specification.

My invention relates to improvements in bunion protectors and has for its object to 10 provide a perforated pad of adjustable thickness, the adjustment of its thickness being such as to relieve the bunion and the adjacent surface of the foot from pressure, and to accommodate such distortion as may 15 be present in the large toe.

In the drawings—

Figure 1 is a perspective view of the inner surface of a device embodying my invention, showing portions broken away.

20 Fig. 2 is a similar view, showing the device without the removable inserts which are shown in Fig. 1, and with the inner protective lining removed.

Fig. 3 is a plan view of one of the inserts. 25 Fig. 4 is a longitudinal view of the device in midsection, showing its application to the foot of the wearer.

As illustrated, I employ the outer shield 5 having the central perforation 6. Upon 30 the inner face of the shield 5 is superimposed the pair of flaps 7—7, arranged before and behind the perforation 6 as shown in Fig. 2. Superimposed upon the flaps 7—7 are smaller flaps 8—8 as shown in Fig. 35 2, the points of attachment of the flaps 8—8 to the flaps 7—7 being indicated by the lines of stitching 9—9, which are further removed from the front and rear of the perforation 6 than are the lines of stitching 40 10—10 by which the flaps 7—7 are secured to the outer shield 5.

The inner protective lining 11 is of the 45 form shown in Fig. 1, having a perforation of the same size as, and registering with, the perforation 6 in the shield 5, the lining 11 having one of its sides cut tangentially from the perforation to its outer edge to form the overlapping flaps 12—12 by means of which said lining 11 is dished or contoured to approximately fit the foot at the 50 point of application for the treatment of the bunion.

Into the various spaces formed by the outer shield 5, flaps 7 and 8 and inner lining 11 inserts 13, approximately of crescent 55 shape, as illustrated in Fig. 3, are placed,

and held by the pressure existing between the foot and the shoe. The lines of stitching 9 and 10 serve to hold inserts 13 contacting with them, at a fixed distance from 60 the perforation 6, in the manner shown in section in Fig. 4.

The formation of the bunion is usually accompanied by a distortion of the great toe, and, the protector being seated in place with 65 the perforation 6 accommodating the apex of the bunion, as shown in Fig. 4, just so many of the inserts 13 will be used in the front portion of the protector as will permit the great toe to lie in a comfortable position with reference to the side of the shoe. 70 The location of the insert 13, toward or away from the perforation 6, will be made solely with reference to the swelling or inflammation existing in the bunion and the 75 contiguous flesh. Under conditions of excessive inflammation the protector may be used without any of the inserts 13 being added, or seated in place; because the structure and location of the flaps 7 and 8 is such 80 as to contour the protector into a dish shape, of the least thickness at its center and around the edge of the perforation 6, and of the greatest thickness front and back of the lines of stitching 9—9. Upon the subsidence 85 of the inflammation and swelling, one or more of the inserts 13 may be employed, front or back of the perforation 6, as may be indicated by the condition of the foot and the conformation of the shoe. 90

The insert 13 is preferably constructed of soft and yielding material, and it may be of any thickness or outline best adapted to the condition of the foot and form of the shoe. 95 Cotton batting may be employed, and such material may be thrust into position without being previously cut or stamped into any particular shape. So that the form of the insert illustrated in Fig. 3 is immaterial, and by the term "insert" as used in the 100 claim I mean to indicate any suitable filler to be used in the spaces between the shield 5 and flaps 7—7, or the spaces between the flaps 7 and 8, or the spaces between the flaps 8—8 and lining 11; or into the space between 105 the shield 5 and lining 11 when the flaps 7 and 8 are omitted from my structure.

The insert 13, as will be seen from the foregoing description, may be withdrawn or replaced as desired whenever the conformation of the protector is to be varied as to thickness. 110

Having thus described my invention, what I claim as new and desire to have secured to me by the grant of Letters Patent, is—

In a bunion protector, in combination a centrally perforated outer shield; a perforated inner lining and a flap secured to the inner face of the shield and between the shield and the lining; and a filler adapted to be removably seated and held in place 10 between said flap and said shield, at a fixed

distance from the perforation in the outer shield.

In testimony whereof, I have signed my name to this specification, in presence of two subscribing witnesses.

ALEXANDER E. BLOCK.
